VELOCIPEDE SADDLE

Harry Golden, New York, N.Y., assignor to Ideas For
Auto and Bike Specialties, Inc., New York, N.Y., a
corporation of New York

Filed July 31, 1967, Ser. No. 8,066

Term of patent 14 years

(Cl. D90—16)

FIG. 1

FIG. 2

FIG. 3

FIG. 4

FIGURE 1 is a front perspective view of a velocipede saddle, embodying my new design;

FIGURE 2 is a rear perspective view thereof;

FIGURE 3 is an enlarged sectional view thereof taken substantially along the line 3—3 of FIGURE 1; and

FIGURE 4 is a rear perspective view of a modified form of velocipede saddle, similar in all respects to FIGURE 1 except for modified reflector means.

I claim:

The ornamental design for a velocipede saddle, as shown and described.
